UNITED STATES PATENT OFFICE.

FRANK N. FORSTER, OF BUFFALO, NEW YORK.

OIL-TANK.

SPECIFICATION forming part of Letters Patent No. 249,918, dated November 22, 1881.

Application filed March 10, 1881. (No model.)

To all whom it may concern:

Be it known that I, FRANK N. FORSTER, of Buffalo, in the county of Erie and State of New York, have invented a new and useful Improvement 5 in Oil-Tanks, of which the following is a specification.

The object of my invention is to provide certain new and useful improvements in tanks for storing petroleum, whereby the tanks will be 10 protected from the effects of lightning.

In the accompanying drawings, Figure 1 is a plan view of an oil-tank provided with my improvements. Fig. 2 is a longitudinal section elevation of the same on the line *x x*, Fig. 1. Fig. 3 is a cross-sectional elevation of the same 15 on the line *y y*, Fig. 1.

Similar letters of reference indicate corresponding parts.

The roof A of the oil-tank B is covered with 20 tarred felt *a*, or paper, or some other material that will make it air-tight, so that none of the gases in the tank can escape through leaks in the roof.

The man-hole gate C has packing *e* to prevent the escape of gas. A pipe, D, is secured 25 to the top of the tank, and this pipe is provided with a pressure-valve, E, that can only be opened by pressure of gas coming from the tank, and thus permit the gas to escape when 30 there is an undue pressure in the tank, and this escaped gas can be conducted into a suitable receptacle. A pipe, F, also is connected to the top of the tank B, and this pipe is provided 35 with a valve, G, which can only be opened by pressure of the air pressing into the tank. This valve is opened automatically as soon as a vacuum is formed in the tank and admits air. A pipe, H, extends from the top of the tank down to within a few inches from the bottom 40 of the same. The level of the oil will rise as high in this tube as in the other parts of the tank, and if a gage-rod, J, is placed into this tube H the height of the oil in the tank can be obtained without causing gas to escape, 45 and without unscrewing or opening the top of the tank.

The inlet-pipe K of the tank B is connected with the ground by a suitable metal connection, L, a short distance from the tank, and between 50 this ground-connection L and the tank B a piece, M, of pipe, of non-conducting or insulating material—such as rubber, glass, &c.—is introduced in the line of the pipe K.

For the purpose of connecting the ends of

the pipe K, to which the insulating-pipe M is 55 fastened, plates N are fastened to the ends of the pipe K, and these plates are connected by a series of rods, O O. These rods are insulated from one of the plates N by washers P, of rubber or other insulating material.

The collars Q Q for holding the insulating-pipe M in place are screwed into recesses in the plates N N as shown in Figs. 1 and 2. The inlet-pipe K enters the tank B at the bottom and extends up to the top of the same on 65 the inside, as shown, or it enters the tank on the top. The outlet-pipe R is also provided with an insulated section and with a ground-connection, in the same manner as the inlet-pipe.

It is well known that a rising quantity of gases attracts lightning, and I have therefore taken all possible precaution to prevent such escape of gases from the oil-tank by means of the devices described. If considerable quantities of gas accumulate in the tank and the pressure increases, the valve E is opened by the pressure, and the gases are conducted to places some distance from the tank. If this gas should become ignited, the valve E prevents any return of the flames into the tank. The valve G admits air when the tank is being emptied, so as to prevent a vacuum being formed in the tank. The level of the oil can be ascertained very conveniently and without permitting any 80 of the gas to escape. If a current of electricity passes along the pipe K, it will pass through the ground-line L into the earth and cannot harm the tank or its contents. The current cannot pass through pipe M, as this is made of non-conducting material, and cannot pass through the rods O O, which are insulated by the washers P, made of non-conducting material.

Having thus fully described my invention, I claim as new and desire to secure by Letters 95 Patent—

The combination, with the inlet and outlet pipes of an oil-tank, of insulating-pipes M, plates N, rods O, connecting the plates, said rods being insulated at one end, and ground-rod L, substantially as described, whereby the tank is insulated from the said inlet and outlet pipes, as set forth.

FRANK NEWTON FORSTER.
